DESIGN FOR A LIQUID PASTEURIZER

Arthur H. Boileau, Cedar Rapids, Iowa, assignor
to Cherry-Burrell Corporation, Wilmington,
Del., a corporation

Application January 15, 1940, Serial No. 89,477

Term of patent 7 years

To all whom it may concern:

Be it known that I, Arthur H. Boileau, a citizen of the United States, residing at Cedar Rapids, in the county of Linn and State of Iowa, have invented a new, original, and ornamental Design for a Liquid Pasteurizer, of which the following is a specification, reference being had to the accompanying drawing, forming part thereof.

In the drawing:

Fig. 1 is a side elevational view of a liquid pasteurizer showing my new design;

Fig. 2 is a front elevational view thereof; and Fig. 3 is a top plan view thereof.

The two sides of the pasteurizing apparatus which are not shown in Figs. 1 and 2 are substantially plain as indicated in Fig. 3.

I claim:

The ornamental design for a liquid pasteurizer, substantially as shown and described.

ARTHUR H. BOILEAU.
